UNITED STATES PATENT OFFICE.

MORRIS TALIANOFF, OF BROOKLYN, NEW YORK.

COMBINATION ROMPER DRESS.

1,405,694.

Specification of Letters Patent. Patented Feb. 7, 1922.

Application filed May 26, 1920. Serial No. 384,288.

To all whom it may concern:

Be it known that I, MORRIS TALIANOFF, a citizen of the United States, residing at Brooklyn, in the county of Kings and State 5 of New York, have invented certain new and useful Improvements in Combination Romper Dresses, of which the following is a specification.

This invention relates to new and useful 10 improvements in children's garments and more particularly to a combination romper-dress, and the primary object of the invention is to provide a device of this character which will allow for ready interchangeability.

A further object of the invention resides 15 in providing a romper to which may be quickly and readily applied a dress, either by buttoning in place or slipping the same 20 thereover.

Still another object of the invention resides 25 in providing "peg-top" bloomers on the romper having pockets therein, the peg-pockets being adapted for projection through slip 30 portions in the skirt.

A still further object resides in providing 35 an article of the type mentioned which is simple in construction, inexpensive to manufacture, and one which will be extremely 40 practicable and useful.

With these and other objects in view my 45 invention consists in the novel features of construction, combination and arrangement of parts as will be hereinafter referred to 50 and more particularly pointed out in the specification and drawings.

In the accompanying drawings, forming a 55 part of this application:—

Figure 1 is a perspective view, partly in 60 section, showing the preferred form of my invention;

Figure 2 is a perspective view showing the 65 rear of the romper with the skirt portion removed;

Figure 3 is a similar view of the skirt removed from the garment;

Figure 4 is a transverse sectional view 70 through the complete romper dress, illustrating clearly the projection of the peg-pockets through the skirt of the dress and the application of the belt to the garment;

Figure 5 is a perspective view illustrating 75 a slightly modified form of the invention;

Figure 6 is a similar view with parts 80 broken away to illustrate clearly the application of the skirt portion to the garment.

Figure 7 is a perspective view of the romper portion of the garment with parts broken away; and

Figure 8 is perspective view of the skirt or 85 dress portion of this form of the garment removed.

In describing the invention, I shall refer 90 to the drawings in which similar reference characters designate corresponding parts throughout the several views, and in which 1 designates a garment for children known generally to the commercial world as a romper, the same having an upper or waist section 2 and a lower or bloomer portion 3. 95 The waist and bloomer portions of the garment, are, as usual, in one piece, and the same may be of simple or fancy design, as desired. As shown in Figs. 1 and 2, the waist section opens in the front and the 100 bloomer portion opens in the rear, but this phase of the structure of the garment is more or less immaterial.

The bloomer portion 3 of the garment is 105 widened at the top to form what are known as "peg-top" bloomers, these peg portions being designated as 4 and formed therein are the pockets 5.

Secured to the waistline portion of the 110 garment at regular intervals therearound are the buttons 6 by means of which a skirt or dress 7 may be applied to the garment, when desired. This dress may be of any design provided at its upper portion with a band 8 in which are provided the button 115 holes 9. The dress is also provided at its sides with slits 10 through which may be projected the peg portions 4 of the bloomers, when the dress is applied to the garment, as clearly shown in Fig. 1 of the 120 drawings.

Secured at its upper edge to the waist portion 2 and in the rear central portion of the latter is a belt 11. This belt is adapted to be buttoned in the front and 125 covers the buttons 6. Thus, when the dress 7 is applied to the garment and the belt 11 properly buttoned in place the means for securing the dress to the garment is obscured from view and the garment looks as 130 if it were made of one piece. When the dress is not in use, this same belt 11 will hide from view the buttons 6 in the same manner.

In Figs. 5 to 8 inclusive, I have shown 135 a slightly modified form of the invention, wherein a set of rompers 12 having a waist

portion 13 and bloomers 14 is provided. As shown herein, the waist portion 13 is slightly different in design from that illustrated in the previously described form. The 5 bloomer portion, however, remains the same having the peg portions 15 and pockets 16 therein. In order to give a neat effect to the bloomers, the waist line of the garment 12 is provided with buttons 17 to which is 10 secured a belt 18.

A dress 19 is also provided having a waist-band 20 thereon to which is secured a pair of strap or suspender sections 21. This dress is adapted to be readily slipped 15 over the romper, the suspender portions 21 resting on the shoulders of the wearer so that the waist-band 20 of the dress will cover the belt 18, giving the effect of a one-piece garment, as illustrated in Fig. 5. 20 This dress 19 is also provided with slits 22 at its sides through which project the peg portions 15 of the bloomers, so that the pockets 16 are in position to be readily engaged by the hands of the child wearing 25 the garment.

From the foregoing it will be seen that I have provided a combination romper dress which is extremely simple in construction and one which will be very practicable in 30 use. With a garment of this character, mothers and nurses will not be confronted with the difficulties and troubles now ex-

perienced in constantly changing children's clothing. A child may be allowed to play in the rompers and without the necessity of 35 changing the garment, the dress may be quickly and readily applied and the child given the appearance of having an entirely fresh and clean garment.

What I claim is:

1. A garment of the class described comprising a romper, the bloomer portions of which are pegged to provide upper projecting portions, said latter portions being provided with pockets, and a dress removably 45 applied to the romper and provided with side slits therein for the projection therethrough of the peg portions of the bloomers.

2. A garment of the class described comprising a romper, the bloomer portions of which are pegged to provide upper projecting portions, said latter portions being provided with pockets, buttons secured to the waist line of said romper, a dress having button holes engaged with said buttons and 55 provided with side slits for the projection therethrough of the pegged portions of the bloomers, and a belt secured intermediate of its ends to the rear of the romper and adapted to cover said buttons to obscure the 60 same from view.

In testimony whereof I affix my signature.

MORRIS TALIANOFF.
